2 SHEETS—SHEET 2.

UNITED STATES PATENT OFFICE.

EDWIN D. CODDINGTON, OF NORTH MILWAUKEE, WISCONSIN.

GROUND FOR CEMENT-COATED WALLS.

1,164,334.

Specification of Letters Patent. Patented Dec. 14, 1915.

Application filed May 1, 1914. Serial No. 835,610.

To all whom it may concern:

Be it known that I, EDWIN D. CODDINGTON, a citizen of the United States, residing at North Milwaukee, in the county of Milwaukee and State of Wisconsin, have invented certain new and useful Improvements in Grounds for Cement-Coated Walls, of which the following is a specification, reference being had to the accompanying drawing, forming a part thereof.

The main objects of this invention are to provide a simple, cheap and convenient substitute for wood and metal lathing, and to facilitate and improve the construction of plastered or cement coated walls.

It consists in the construction, arrangement and combination of parts as herein-after particularly described and pointed out in the claims.

In the accompanying drawing like characters designate the same or similar parts in the several figures.

Figure 1 is a side elevation of one of the preferred embodiments of the invention, showing portions of two adjoining wire reinforced sheets; Fig. 2 is a cross section on the line 2—2, Fig. 1, showing the ground or backing partially coated with cement on opposite sides; Fig. 3 is a cross section on the line 3—3, Fig. 1, showing one of the preferred methods of connecting the lapped sheets; Fig. 4 is an elevation of a modified embodiment of the invention specially designed for roofing or similar purposes where the ground or backing is to be coated on one side only; Fig. 5 is an elevation of another modification showing a different arrangement of the reinforcing wires; Fig. 6 is a section on the line 6—6, Fig. 5; Fig. 7 is an elevation showing another method of fastening adjoining lapped sheets together and to a girt or frame member; Fig. 8 is a like view of another modification; and Fig. 9 is a similar view showing portions of adjoining lapped sheets with reinforcing wires extending across the lap and interwoven through both sheets and with one another.

Referring to Figs. 1 and 2, showing a construction of the ground or backing doubly reinforced and specially designed to receive a plastic coating on both sides, *a* designates flexible sheets of fibrous material, such as commercial building felt or paper, which is ordinarily and preferably saturated or coated with a tar product or the like, to render it waterproof. These

sheets are reinforced at intervals by wires to render them sufficiently stiff and stable to receive a coating of plaster or cement on each or either side when the ground or backing is spread upon and attached to the framework of a wall or partition the members of which may be spaced according to the nature of the structure more or less widely apart, thereby effecting not only a saving in material, but also in the time and labor required for erection.

In the present case the ground or backing sheets *a*, are each provided with three series or sets of reinforcing wires *b*, *c* and *d*. The wires *b* are woven at suitable intervals in and out through the sheets *a*, preferably parallel with one another and at an oblique angle to the longitudinal edges of the sheets at or adjacent to which they terminate. The wires *c* and *d* of the other two sets or series are interwoven with the sheets *a* and wires *b* alternately on opposite sides of the sheets, and preferably parallel and equidistant from one another at an oblique angle to the longitudinal edges of the sheets and to the wires *b*. The wires *c* are preferably located entirely on one side of the sheets *a*, while the wires *d* are located entirely on the opposite side of the sheets, and they may be inserted underneath all of the wires *b*, which they cross, as shown, or they may be woven in and out underneath and over some of the wires *b*, or like the wires *b* through the sheets, to more securely confine them in place on the sheets before the plaster or cement coating is applied thereto. Hard drawn or resilient wire is preferably used for the reinforcement of this form of the ground or backing, which may be prepared in a shop or factory ready for use, and rolled for storage and transportation, the wires assuming a spiral form when the sheets are rolled, but on account of their resiliency resuming a straight form when the sheets are unrolled and spread flat. The sheets are lapped when or before they are applied to the framework of a wall, and are fastened together along their lapped edges in various ways.

As shown in Figs. 1 and 3, where the sheets *a* are separately reinforced by wires terminating at their ends at or adjacent to the longitudinal edges of the sheets, the lapped portions of adjoining sheets may be fastened together by a sheet metal strip *e*, having prongs *f* passing through the sheets

and clasped over a wire *g* on the opposite side of the backing. This method of fastening is specially designed for use where the lapped joint between the sheets is unsupported by a girt or frame member.

Where the lapped joint overlies a girt or frame member, such as *h*, as shown in Figs. 7 and 8, the lapped edges of adjoining sheets may be fastened thereto by nails alone, by a wire or rod *i*, secured at intervals by staples *j* to the girt or frame member, as shown in Fig. 7, or by a metal band *k*, nailed at intervals to the girt or frame member, as shown in Fig. 8.

Two or more lapped sheets may be fastened and held together in the proper relation to one another by reinforcing wires, as shown in Fig. 9, without other fastenings at the lapped joints, one or more sets of the reinforcing wires extending continuously across the adjoining sheets. When so connected the sheets may be rolled together as one, for storage and transportation.

For certain purposes, as when the ground or backing sheets are to be coated on one side only, one or both of the extra sets of reinforcing wires *c* and *d* may be omitted, and the wires may be spaced more or less closely. Wires of different sizes and different shapes in cross section may also be used for reinforcement of the same sheets, larger wires or rods alternating with smaller wires or rods, or being placed at more or less frequent intervals, according to varying conditions and requirements.

For roofing or other purposes, where the ground or backing sheets *a*, are to be coated on one side only, and where an imperforate water tight base or foundation is desirable, the wire reinforced sheets *a*, may be backed by an extra sheet *l*, of building felt, paper or other suitable material, attached thereto by any suitable adhesive substance such as cement, tar, pitch or the like, as shown in Fig. 4. In this case the sheet *a* has but one extra set of reinforcing wires *c*, which are applied thereto on the side opposite the backing sheet *l*, but sheets reinforced as shown in Fig. 1, may be provided with backing sheets cemented thereto.

The reinforcing wires may be applied to the sheets at right angles to and parallel with their longitudinal edges, as shown in Fig. 5. In this case, in which the sheets are not intended to be rolled for transportation or storage, the wires are not necessarily hard drawn or resilient, but may be more or less annealed and flexible. With this arrangement, in which the cross wires *b'* are threaded or woven at intervals through the sheet *a*, and the longitudinal wires *c'* and *d'* are interwoven with the sheet and with the wires *b'* on opposite sides of the sheet, either or both sets of the extra reinforcing wires *c'* and *d'* may be omitted.

In the several embodiments of the device herein shown and described, the wires *b* or *b'* being threaded or woven at intervals through the sheets *a*, form an integral structure, and no extra fastenings are required to 70 secure the wires to the sheets, the wires being held in place by frictional engagement with one another and with the faces of the sheets. The threading or weaving of the wires *b* or *b'* through the sheets, and the interweaving or insertion of the extra reinforcing wires *c* or *c'* and *d* or *d'* between the wires *b* or *b'* and the sheets, cause the sheets to assume a corrugated undulatory, or wavy form, as shown in Figs. 2 and 6. 80 This gives the plastic coating *m*, applied to one or each side of the sheet, a corresponding corrugated undulatory, or wavy form, which materially stiffens and strengthens it between the members of the framework to 85 which the ground or backing sheets are attached, so that much wider spaces may be spanned than would otherwise be practicable with a comparatively thin coating of plastic material, the ridges or thicker portions of 90 the coating acting as beams or trusses between the supporting members of the framework.

While the coating *m* of plastic material will adhere with tenacity to the rough fibrous surfaces of the sheets *a*, it is further secured thereto by the reinforcing wires around which it flows, and which are embedded therein, the plaster or cement forming keys or clenches around and enveloping 100 the wires and sealing the openings in the sheets, as shown in Fig. 2, without waste of material in the formation of the keys or clenches.

The wires *b*, *c* and *d* and the wires *b'*, 105 whether they terminate at the edges of the sheets *a*, as shown in Figs. 1, 5, 7 and 8, or cross adjoining sheets as shown in Fig. 9, extend across the lapped portions of adjoining sheets to which they are attached, and form continuous reinforcements in the direction of the length of such wires spanning the joints between the sheets.

Various modifications in minor details of construction other than those specifically 115 shown and mentioned, may be made without departure from the principle and scope of the invention as defined in the following claims.

The term "cement" as herein employed, is used in its generic sense, and includes any plastic material suitable for the purpose, and the term "wall" is intended to include horizontal, perpendicular and inclined structures, such as the outside walls, partitions, floors, ceilings and roofs of buildings.

I claim:

1. A ground for cement coated walls comprising a continuous flexible sheet of fibrous material having an undulatory surface on 120

its opposite faces and constituting a permanent element of the ground, and reinforcing wires woven at intervals through the undulatory body of the sheet.

5 2. A ground for cement coated walls consisting of a flexible sheet of fibrous material, having an undulatory surface on its opposite faces and constituting a permanent element of the ground, a series of reinforcing wires woven through said undulatory sheet at intervals, and a second series of wires interwoven with the sheet and the wires of the first series.

15 3. A ground for cement coated walls consisting of a flexible sheet of fibrous material, having an undulatory surface on its opposite faces and constituting a permanent element of the ground, a series of reinforcing wires woven through said undulatory sheet at intervals, and two other series of wires interwoven with the sheet and the wires of the first series on opposite sides of the sheet.

25 4. A ground for cement coated walls consisting of a flexible sheet of fibrous material having an undulatory surface on its opposite faces and constituting a permanent element of the ground, and resilient reinforcing wires woven at intervals through said undulatory sheet at an oblique angle to its length.

35 5. A ground for cement coated walls consisting of a flexible sheet of fibrous material having an undulatory surface on its opposite faces and constituting a permanent element of the ground, a series of resilient reinforcing wires woven at intervals through said undulatory sheet at an oblique angle to its length, and a second series of resilient reinforcing wires interwoven with the sheet and the wires of the first series at an oblique angle thereto.

45 6. A ground for cement coated walls consisting of a flexible sheet of fibrous material having an undulatory surface on its opposite faces and constituting a permanent element of the ground, a series of resilient reinforcing wires woven at intervals through said undulatory sheet at an oblique angle to its length, and two other series of resilient wires interwoven with the sheet and the wires of the first series at an oblique angle thereto and on opposite sides of the sheet.

7. A ground for cement coated walls consisting of lapped flexible sheets of fibrous material having an undulatory surface on opposite faces and constituting a permanent element of the ground, and reinforcing wires woven at intervals through said sheets and extending across the lap between them, the 60 wires of one sheet crossing the overlapping edge of the adjoining sheet and forming a continuous reinforcement across the joint between the sheets.

8. A ground for cement coated walls consisting of lapped flexible sheets of fibrous material having an undulatory surface on opposite faces and constituting a permanent element of the ground, and resilient reinforcing wires woven at intervals through 70 said undulatory sheets and crossing the lap between them at an oblique angle.

9. A ground for cement coated walls consisting of lapped flexible sheets of fibrous material having an undulatory surface on 75 opposite faces and constituting a permanent element of the ground, reinforcing wires woven at intervals through the undulatory sheets and extending across the lapped edges thereof, and a metal reinforcement running 80 lengthwise of and fastened at intervals to the lapped portions of the sheets.

10. A ground for cement coated walls consisting of lapped flexible sheets of fibrous material, a series of reinforcing wires woven 85 at intervals through said sheets and extending across the lapped edges thereof, a lap reinforcing wire arranged lengthwise of the lapped edges of the sheets on one side thereof, and a metal band placed on the opposite 90 side of the lapped sheets and formed with prongs which pass through the sheets and are clasped over said lap reinforcing wire.

11. A ground for cement coated walls consisting of a flexible sheet of fibrous material, reinforcing wires woven at intervals 95 through said sheet, and a backing sheet cemented to one side of the first sheet and sealing the openings made therein by the reinforcing wires.

In witness whereof I hereto affix my signature in presence of two witnesses.

EDWIN D. CODDINGTON.
